PACKING TRAY

Howard K. Prentice, Yakima, Wash., and Walter
J. Schwertfeger, West Englewood, N. J.

Application June 4, 1952, Serial No. 20,026

Term of patent 14 years

(Cl. D58—13)

To all whom it may concern:

Be it known that we, Howard K. Prentice and Walter J. Schwertfeger, both citizens of the United States of America, residing at Yakima, county of Yakima, State of Washington, and West Englewood, county of Bergen, State of New Jersey, respectively, have invented a new, original, and ornamental Design for a Packing Tray, of which the following is a specification, reference being had to the accompanying drawing, forming part thereof.

Fig. 1 is a bottom plan view of a packing tray, shown partially broken away for purpose of convenience, showing our new design;

Fig. 2 is a rear elevational view, partly in section and partly in full, taken on the line 2—2 of Fig. 1 with portions shown broken away for convenience of illustration.

It is understood that the configuration of the individual elements of the packing member, as shown by the shaded area, is the same throughout the entire packing member.

What is claimed is:

The ornamental design for a packing tray, as shown and described.
